J. P. BAUMGARTNER.

GARTER FASTENER.

APPLICATION FILED FEB. 12, 1919.

1.317.677.

Patented Oct. 7, 1919.

Thos. Parke,

By W. Steele Jackson,

Attorney

UNITED STATES PATENT OFFICE.

JOSEPH P. BAUMGARTNER, OF PHILADELPHIA, PENNSYLVANIA.

GARTER-FASTENER.

1,317,677.

Specification of Letters Patent.

Patented Oct. 7, 1919.

Application filed February 12, 1919. Serial No. 276,696.

To all whom it may concern:

Be it known that I, JOSEPH P. BAUMGARTNER, a citizen of the United States, residing at Philadelphia, in the county of Philadelphia and State of Pennsylvania, have invented a certain new and useful Garter-Fastener, of which the following is a specification.

My invention relates to devices intended 10 to secure a garter to a stocking, or for similar use, in which one part of the fastening is placed inside the stocking and the other outside, the stocking being secured between them.

15 The purpose of my invention is to simplify and cheapen the fastener and render the structure more compact.

Further purposes will appear in the specification and in the claims.

20 I have preferred to illustrate my invention by but one form, selecting a form which is practical, efficient and inexpensive and which at the same time well illustrates the principles of my invention.

25 Figures 1 and 2 are front elevations of the catch, the outside, perforated, encircling or gripping member, showing the parts in different positions.

Figs. 3 and 4 are a side elevation and a 30 central, longitudinal section with the perforated member in position about the button.

Fig. 5 is a section upon line 5—5 of Fig. 3.

Figs. 6 and 7 are front and rear elevations of the catch.

35 Fig. 8 is a side elevation of the structure seen in Figs. 6 and 7.

Figs. 9, 11 and 12 are perspective views of parts entering into the construction shown.

40 Fig. 10 is a bottom plan view of the structure seen in Fig. 9.

Fig. 13 is a rear elevation of a guard ring used in connection with the structure in Figs. 6-8.

45 Fig. 14 is a fragmentary view of the rear loop ready for insertion of the button plate.

In the drawings similar numerals indicate like parts. My garter clasp comprises generally two members, a button or rear member 50 and a perforated inclosing or encircling front member, each carried by a depending garter strap or loop.

The button 15, having head 15' and neck 15" is supported upon a plate 16, whose 55 lower edge 17 rests in the bend 18 of a loop 19 which is passed at its middle portion

about the suspending bar 20 and extends downwardly at 21 to the bend 18 and thence upwardly at 22 to some point above the fastener, here in proximity to the suspending loop. The button passes through an aperture 23 in the loop portion 22, so as to project from the strap formed and be in position for engagement by the catch.

The front member includes a movable 65 catch 24, extending through the two parts of a fabric loop forming a part of the loop 19 and extending downwardly at 25 and upwardly at 26 to a point above the fastener, here approximately to the supporting bar 70 20. The movable catch (operating) part 24 passes through both sides 25 and 26 and is secured therein by a collar 27 which is cemented or otherwise secured about the lower edge 28 of the catch. As it is desirable 75 to form these parts of celluloid or similar material, the collar may be secured in position by collodion or by any other effective means. Obviously the parts may be made of metal if desired, giving a further range of 80 attaching means.

The catch is provided with one or more, here two projections 29 connected with the catch by necks 30 and is held in position at the front and protected against actuation 85 through improper engagement with the clothing here by a front plate 31. This has notches 32 for reception of the necks 30. The intermediate rim sections 33 restrict the passage for the necks 30 with the result that 90 these neck portions snap into the grooves or depressions 32 and are retained in these positions at both ends of the movement corresponding to the open and closed position of the fastener.

95 The front protecting plate 31 is secured in position by tangs 34 which are passed through the openings 35 of a retaining washer or plate 36, and are clenched within the recesses 37. In the construction shown 100 the tangs are extended through but one of the fabric thicknesses, going through 25 only.

The catch 24, cap 31 and washer 35 are all provided with oval openings of size and 105 shape adapted to permit the passage of the oval head 15' of the button. Of these the only one in which the size and shape of the opening is of practical importance is the catch 24, the lesser axis of whose preferably 110 elliptical opening must be smaller than the major axis of the head 15' of the button, in

order that it may engage within the neck of the button when turned.

In operation, the major axis of the button lies vertically, corresponding with the opening in the catch 24 and cap 31 as shown in Fig. 1. The fabric of the stocking is placed over the button and the button with the fabric covering is then passed through the openings to the position seen in Figs. 10 3 and 4. The catch is then turned, in a counterclockwise direction as shown, to the position seen in Fig. 2, the sides of the oval opening of the catch fitting the neck of the button and retaining the parts in the position shown in Fig. 4. In this figure the fabric has been omitted for clearness.

It will be evident that the front fabric length of the rear loop by which the button support 16 is covered, forms a resilient backing for the stocking when clasped and that both thicknesses of the fabric forming the front loops afford resilience to the catch, effective to permit the catch to turn from one position of notch engagement to the other and retaining it in each of its positions. Thus advantage is taken of the front loop at the same time that the catch is passed completely through it, giving a compactness of catch structure not otherwise attainable and considerably reducing the thickness of the device, as compared, for example, with that shown in my Patent No. 1,278,292, dated September 10, 1918.

Having thus described my invention, what I claim as new and desire to secure by Letters Patent is:

1. In a garment clasp, an oval button, a flat support therefor, a rear fabric loop about the support, a front fabric loop, a catch passing through the front fabric loop and having an oval opening and a cover for

the catch secured to the front fabric of the front loop.

2. In a garment clasp, an oval button, a flat support therefor, a rear fabric loop about the support, a front fabric loop, a catch passing through the front fabric loop and having operating extensions and an oval opening and a cover for the catch providing space for movement of the operating extensions and additional space for said extensions at each extremity of their movement.

3. In a garment clasp, an oval button grooved about the ends of its major axis, a flat support therefor, a rear fabric loop folded about the end of the support and apertured for the button, a front fabric loop, a catch for the button having an oval opening and passing through the loop to turn therein, operating extensions on said catch engaging the front face of the front fabric loop and retaining means for the catch secured to the front fabric loop, affording room for oscillation of the operating extensions and additional room for said extensions at each end of their movement to retain them in these positions by reason of the resilience of the fabric of the front loop.

4. In a garment clasp, an oval button, a support therefor, fabric secured to the support and covering the front thereof, a catch for the button having an oval opening and adapted to oscillate to engage the button, and having front and rear flange surfaces and a fabric loop lying between these flange surfaces and pressing against them, in combination with a cover for the catch engaging the fabric of the loop and retaining the catch through the resilience of the fabric in its positions at the ends of its movement.

JOSEPH P. BAUMGARTNER.
